UNITED STATES PATENT OFFICE.

JOHN REGAN, OF NEW BEDFORD, MASSACHUSETTS, ASSIGNOR TO CROMPTON & KNOWLES LOOM WORKS, OF WORCESTER, MASSACHUSETTS, A CORPORATION OF MASSACHUSETTS.

DESIGN FOR A DROP-WIRE FOR LOOM-STOP MOTION.

58,821.

Specification for Design.

Patented Aug. 30, 1921.

Application filed April 15, 1920. Serial No. 374,235. Term of patent 14 years.

To all whom it may concern:

Be it known that I, JOHN REGAN, a citizen of the United States, residing at New Bedford, in the county of Bristol and State of Massachusetts, have invented a new, original, and ornamental Design for a Drop-Wire for Loom Stop-Motion, of which the following is a specification, reference being had to the accompanying drawing, forming

part of this specification, which is a front elevation of a drop wire showing my new design.

I claim:—

The ornamental design for a drop wire for loom stop motion, as shown.

In testimony whereof I have hereunto affixed my signature.

JOHN REGAN.
